UNITED STATES PATENT OFFICE.

CHARLES R. HUDSON, OF WARREN, INDIANA.

CLARIFYING APPARATUS.

SPECIFICATION forming part of Letters Patent No. 681,170, dated August 20, 1901.

Application filed December 13, 1900. Serial No. 39,645. (No model.)

To all whom it may concern:

Be it known that I, CHARLES R. HUDSON, a citizen of the United States, and a resident of Warren, in the county of Huntington and State of Indiana, have invented a new and Improved Clarifying Apparatus, of which the following is a full, clear, and exact description.

This invention relates to improvements in apparatus for heating and clarifying oil. In preparing oil for shipment from the tanks in the fields in the pipe-line companies' lines it is necessary throughout the winter season or during cold weather to heat the oil. The salt water mixed with the oil must be "settled out." Otherwise it would gather in the lines, freezing and bursting them, and, further, in all seasons of the year crude oil is liable to be "cut"—that is, agitated with water or by certain kinds of friction it becomes coagulated or paraffined and called in the oil-fields "roily oil," containing "B. S." in which case it becomes necessary to apply heat to clarify or settle the "B. S." The method of heating a tank of oil in general use in the oil-fields is by steaming it, and generally twenty-five-horse-power boilers are used for this purpose in connection with other operations of the well or plant. To steam a tank of oil, connections are made with the boiler and the tank, putting the pipe down through the oil close to the bottom of the tank. A quantity of salt water is retained in the bottom of the tank, and the steam is turned on, but into the salt water, it being considered injurious to the oil to permit steam to come into direct contact with it. When the oil is very roily, after heating it to a high temperature it is allowed to stand for a day or two, and if during that time it does not settle out clear the heating process must be repeated.

It is the object of my invention to obviate the above difficulties by providing a means by which the oil may be more quickly heated and clarified and at a considerable less expense of time and fuel.

I will describe a clarifying apparatus embodying my invention and then point out the novel features in the appended claims.

Reference is to be had to the accompanying drawings, forming a part of this specification,

in which similar characters of reference indicate corresponding parts in both figures.

Figure 1 is a sectional elevation of an apparatus embodying my invention and showing the parts in position for spraying water on the oil, and Fig. 2 is a sectional elevation showing the parts in position for forcing a column of water through the oil.

Referring to the drawings, 1 designates an oil-tank of any desired capacity, and 2 indicates a heater, on which is a boiler 3, preferably of the tubular type. From the dome 4 of the boiler a pipe 5 leads to and is designed to discharge into the upper portion of the tank. Mounted to rotate on the end of this pipe 5 is a tube 6, on one end of which is a column-discharging nozzle 7 and on the other end is a spray-discharging nozzle 8. The discharge from these nozzles may be controlled by valves 9, 10.

Leading from the interior of the tank at the bottom to the boiler 3 is a pipe 11, in which is a cut-off valve 12 and check-valve 13. Within the tank the pipe 11 has a vertically-swinging extension 14, from which a lifting device, such as a chain 15, extends upward to the top of the tank.

In operation when the tank of oil is ready for heating the valve 12 is opened and the salt water in the bottom of the tank will flow through the check-valve 13 to the boiler 3. The heat from the furnace or heater 2, which may be gas heat, coal, coke, or wood, within a few minutes will cause an expansion of the fluid and force a current thereof through the pipe 5 into the tank. If the oil is in good condition at the beginning and only requires to be heated, the swinging connection 14 is to be left with its end in the salt water and the nozzle 7 turned on to discharge into the tank, so that a solid column of water will pass through the oil, as indicated in Fig. 2. This starts a gentle circulation of the oil, as indicated by the arrows, which circulation is always in the same direction and does not agitate or churn the oil, and consequently does not "roil" it. When the oil is not in good condition or somewhat roily previous to heating, after it becomes thoroughly hot by the use of the solid column, as shown in Fig. 100

2, then turn on the spray-nozzle, as shown in Fig. 1. This will cause a spraying of the salt water on the top of the oil, which passing through the oil will carry all heavy matter or 5 impurities to the bottom of the tank.

If the oil is very bad or contains a large quantity of "B. S." the water is first to be discharged into the oil through the nozzle 7, and after it begins to circulate nicely the 10 swinging portion 14 of the pipe 11 is to be raised into the oil to permit the oil to pass through the heater. After raising the oil to a high temperature, the section 14 of the pipe is to be again lowered and the spraying-nozzle 15 is to be brought into position to spray water onto the oil, which causes it to become clear. When the oil is ready for shipment, the valve 12 is to be closed and a drainage-cock 16 is opened, permitting the salt water 20 to escape from the heater and the pipes.

Having thus described my invention, I claim as new and desire to secure by Letters Patent—

1. In an apparatus for clarifying oil, an oil-25 tank, a heater, a pipe extended from said heater over the oil-tank, a column-nozzle connecting with said pipe, a spray-nozzle connecting with said pipe, and a pipe leading from the lower portion of the tank to the 30 heater, substantially as specified.

2. An apparatus for clarifying oil, comprising an oil-tank, a heater, a pipe leading from the upper portion of said heater and adapted to discharge into the tank, and a pipe leading 35 from the lower portion of the tank to the

heater, the said pipe having a swinging connection within the tank, substantially as specified.

3. An apparatus for clarifying oil, comprising an oil-tank, a heater, a pipe leading from 40 the upper portion of said heater over the tank, a tube mounted to rotate on the end of said pipe, a column-nozzle on one end of said tube, a spray-nozzle on the other end of said tube, and means for conducting a liquid from said 45 tank to the heater, substantially as specified.

4. An apparatus for clarifying oil, comprising an oil-tank, a heater, a boiler on the heater, a pipe leading from the dome of said boiler over the tank, a spray-nozzle on said pipe, a 50 column-nozzle on said pipe, and a valve-controlled pipe leading from the lower portion of the tank to the boiler, substantially as specified.

5. An apparatus for clarifying oil, comprising an oil-tank, a boiler, a pipe leading from the lower portion of the tank to the lower portion of the boiler, a swinging section on said pipe within the tank, a chain or the like extended from said swinging section upward 60 through the tank, and a pipe leading from the upper portion of the boiler to the upper portion of the tank, substantially as specified.

In testimony whereof I have signed my name to this specification in the presence of 65 two subscribing witnesses.

CHARLES R. HUDSON.
